UNITED STATES PATENT OFFICE

2,096,821

FURNACE

John H. Noble, Parchment, Mich.

Application June 30, 1936, Serial No. 88,183

4 Claims. (Cl. 126—110)

The main objects of my invention are:

First, to provide a hot air furnace of the oil burning type, characterized by the efficiency thereof.

5 Second, to provide a furnace of the type described, having a relatively large tubular heating area and a ready circulation of air thereby.

Third, to provide a furnace of the type described, which is composed of parts readily disassembled for cleaning purposes.

10 Fourth, to provide a furnace of the type described, characterized by novel provisions for pre-heating the combustion air therefor.

Fifth, to provide a furnace having improved 15 humidity regulation.

Further objects relating to details and economies of my invention will definitely appear from the description to follow. The invention is defined in the claims.

20 A preferred embodiment of my invention is illustrated in the accompanying drawing, wherein:

Fig. 1 is a vertical sectional view through a furnace embodying my invention, on the line 1—1 of Fig. 2.

25 Fig. 2 is a horizontal section on the line 2—2 of Fig. 1, illustrating the arrangement of the tubes and combustion gas manifold of my furnace.

Fig. 3 is an enlarged fragmentary view partially in section, illustrating a detail of the tube construction of my improved furnace.

The present invention is concerned with the production of an improved hot air furnace of the oil burning type, although the essentials of the invention are not restricted to the oil burning 35 type of furnace and may equally well be applied in connection with systems embodying different types of combustion, for instance, coal, gas, etc. The furnace is characterized by the unusually large heating contact area furnished by a plurality of U-shaped upstanding tubes of relatively small diameter per se, said tubes extending substantially of the height of the furnace casing and being readily removable and taken down for cleaning purposes.

40 Further, my invention comprises novel provisions whereby the manifold for receiving products of combustion from a combustion chamber may be thoroughly and quickly cleaned. Other aspects of my invention will become apparent 45 from the description to follow.

45 Referring to the drawing, the reference numeral 1 indicates a cylindrical sheet metal casing having a conical dome 2 provided with hot air conduit collars or nipples 3 radiating therefrom. The casing is closed by a removable sheet

metal top 4. 5 represents the floor of a basement or other room housing the furnace.

Supported on suitable legs or uprights 6, I mount a combustion chamber, generally indicated 7, consisting of a dome 8 and floor 9. The 5 chamber is suitably lined with fire clay, fire brick or other analogous material 10. An opening is formed in the bottom of the combustion chamber to receive the burner 11, preferably an oil burner. Alternatively, as stated above, the oil burner may 10 be replaced by a gas burner or the chamber may be provided with a grate for coal, coke or other materials. Combustion air is supplied around the burner through a conduit 12 joining the opening in the bottom of the combustion chamber and 15 leading from a blower 112 encased in a housing 13.

The combustion chamber 7 is provided at the top thereof with a plurality of openings 14 into which is inserted one end or leg of a number of U-shaped tubes generally indicated 15. The 20 number of the tubes is relatively large, as indicated in Figs. 1 and 2, and the tubes are of substantial length so that they extend throughout the greater part of the height of casing 1. An annular manifold 16 surrounds and is spaced 25 from combustion chamber 7, being suitably supported by lugs 17 attached to bottom 9 of the combustion chamber or by other rigid supporting means which will readily suggest themselves.

Manifold 16 is preferably formed of a single 30 casting and is provided with a number of openings in the top thereof, corresponding to the number of openings in the top of the combustion chamber, for the purpose of receiving the other leg of the U-shaped tubes 15. The tubes are provided with a machined taper at the bottom of each of their legs, whereby they may be readily fitted in and removed from the chamber and manifold for the purpose of brushing or cleaning the same internally and externally. The construction of the upper or bight ends of the tubes is clearly illustrated in Fig. 3, consisting of a U-shaped double elbow 18 joined to the individual straight uprights 19 by a machine fit joint 20. Thus, not only may the U-shaped tubes, generally 45 indicated 15, be removed as a whole from their connection with chamber 7 and manifold 16, but also the tubes may be separated into their simplest elements for the purpose of cleaning.

For the purpose of facilitating the cleaning of 50 manifold 16 interiorly thereof, I have provided a plurality of clean-out passages 21 preferably integral with the manifold casting and extending tangentially of the same outwardly to openings 22 provided in the jacket. Removable doors 23 nor- 55

mally close the openings. It will be appreciated that this construction betters the construction wherein the clean-out passages extend radially of the furnace casing, inasmuch as a straight cleaning implement may be inserted conveniently, eliminating the difficulties caused by the presence of bends between the passages and manifold.

The products of combustion are exhausted from manifold 16 through a suitable flue 121.

10 Air is supplied to the casting at the left side thereof, as viewed in Fig. 1, by means of a suitable blower 24 whose inlet is shown at 25. The outlet of the blower communicates with casting 1 at a point adjacent manifold 16 at the bottoms 15 of tubes 15. Accordingly, the air supplied to casting 1 has a full sweep around the heating tubes 15 and is heated to a maximum extent thereby prior to its exit through the hot air pipes or conduits into the rooms desired to be heated. At 20 the same time the incoming air prevents the tubes from becoming overheated adjacent the manifold.

The reference numeral 26 indicates a conduit communicating with a fitting 27 adjacent an opening 28 in the casing wall, the conduit being 25 for the purpose of leading preheated combustion air to blower 13 which delivers it to burner 11. This provision substantially increases the efficiency of combustion particularly when liquid fuel is employed.

30 Tubes 15 furnish a support adjacent their upper end for a humidifying trough 29 which is adjustably mounted on the tubes by means of clamps 30. The supply of liquid to the humidifying trough is made possible by means of a bent 35 metal pipe 31 carried by the casing and the supply is governed by means of a humidostat 32, preferably of the wood block expanding type, which is mounted in another room in a manner that will be understood. Flexible tube 33 connects the humidostat with valve 34 controlled 40 thereby.

In the above described construction, the difficulty normally attendant on cleaning a furnace is reduced to a minimum, due to the improved 45 shape of the manifold, as well as the ready removability of fire tubes 15.

Efficiency of combustion is greatly improved by the nature of the tubes themselves as well as by their mounting with respect to the manifold. I 50 have found that a large number of connecting tubes 15 of relatively small diameter and extending substantially lengthwise of the casing, as embodied in my invention, results in optimum heating. This result is enhanced by the arrangement for preheating combustion air, which is an 55 important feature of my invention. The employment of a blower in this combination permits the use of tubes or flues for the products of combustion of relatively small diameter and the uniform 60 discharge of the products of combustion therethrough. The air entering the casing circulates freely across the tubes which provide a large radiating surface. As the heat of the products of combustion is not relied upon to insure circulation thereof, the maximum of heat units may be utilized without affecting the discharge of the 65 products of combustion.

I have illustrated and described my improvements in an embodiment which I have found 70 very practical. I have not attempted to illustrate or describe other embodiments or adaptations as it is believed this disclosure will enable those skilled in the art to embody or adapt my improvements as may be desired.

Having thus described my invention, what I claim as new and desire to secure by Letters Patent is:

1. In a furnace, a combustion chamber having a burner therein, said chamber having a plurality of closely spaced openings at the top thereof, an annular manifold surrounding and spaced from said combustion chamber and having a plurality of openings at the top thereof, a plurality of closely spaced U-shaped tubes of relatively small 10 diameter and having the legs thereof extending downwardly, one leg in an opening in the combustion chamber and the other in an opening in the manifold, said tubes being adapted to receive the combustion gases from the chamber and circulate 15 them upwardly a substantial portion of the furnace height and downwardly into the manifold, a closed casing surrounding said chamber, manifold and tubes, means for supplying air to said casing above said manifold and adjacent the 20 bottom of said tubes, and means for circulating preheated combustion air from the casing to the burner, said circulating means including means positioned to receive and withdraw air after it passes and is heated by said tubes. 25

2. In a furnace, the combination with a casing, of a combustion chamber disposed centrally at the bottom of the casing, an annular flue manifold surrounding said combustion chamber, a plurality of U-shaped tubes of relatively small 30 diameter arranged in an annular series with their inner legs opening to the top of said combustion chamber and their outer legs opening to the top of said flue manifold, a burner at the bottom of said combustion chamber, a cold air supply blower 35 discharging into said casing across said tubes, and a blower for supplying preheated air to said burner and having an intake connected to said casing at an elevated position relative to the discharge of the cold air supply blower and in a position to receive and withdraw the air after it 40 passes said tubes.

3. In a furnace, the combination with a casing, of a combustion chamber disposed centrally at the bottom of the casing, an annular flue manifold surrounding said combustion chamber, a plurality of U-shaped tubes of relatively small 45 diameter arranged in an annular series with their inner legs opening to the top of said combustion chamber and their outer legs opening to the top 50 of said flue manifold, a burner at the bottom of said combustion chamber, a cold air supply blower discharging into said casing across said tubes, and a blower for supply preheated air to said burner and having an outlet communicating with 55 said burner and an intake connected to said casing opposite said cold air supply blower and at an elevated position relative to the discharge of the cold air supply blower.

4. In a furnace, a casing having therein a 60 combustion chamber and a manifold for receiving the combustion gases, means connecting said chamber and manifold, comprising a plurality of closely spaced tubes of relatively small diameter 65 inserted in said chamber and manifold, respectively, means for supplying air to be heated to said casing comprising an air supply member communicating with one side of said casing adjacent the point of junction of the tubes with the manifold, and means for supplying combustion air to said chamber and comprising an air receiving flue communicating with said casing on the side thereof opposite said supply means. 70

JOHN H. NOBLE.
